UNITED STATES PATENT OFFICE.

EDWARD E. ROSE, OF SWISSVALE, PENNSYLVANIA, ASSIGNOR TO WESTINGHOUSE ELECTRIC AND MANUFACTURING COMPANY, A CORPORATION OF PENNSYLVANIA.

LIQUID-SEALED VALVE.

1,215,579.

Specification of Letters Patent. Patented Feb. 13, 1917.

Application filed June 9, 1914. Serial No. 844,105.

To all whom it may concern:

Be it known that I, EDWARD E. ROSE, a citizen of the United States, and a resident of Swissvale, in the county of Allegheny and State of Pennsylvania, have invented 5 a new and useful Improvement in Liquid-Sealed Valves, of which the following is a specification.

My invention relates to liquid-sealed 10 valves of the character employed to control the connection between vacuum pumps and the interiors of highly evacuated containers, such as vapor rectifiers.

The object of my invention is to provide 15 a valve of the character specified that will permit a free flow of gas from the container to the pump during evacuation, at the same time preventing leakage from the surrounding atmosphere, and that may be 20 readily manipulated to cut off the free passage to the pump at the end of the evacuating process. Furthermore, I provide means whereby a liquid sealing medium may be admitted to the valve passages on 25 the pump side after closure, effectively preventing the passage of gas to the interior of the container.

In the accompanying drawing, Figures 1 and 2 are views, in section, of my valve in 30 the open and sealing conditions, respectively; and Figs. 3 and 4 are views, in plan, of the valve in the positions corresponding to Figs. 1 and 2, respectively. The section plane of Fig. 1 is shown by the broken line 35 II-II in Fig. 3.

For the successful operation of vapor rectifiers and similar apparatus, it is essential 40 that a vacuum of extremely high degree be produced and maintained within the container. I have found that valves of the ordinary character composed of metal parts packed with oil are entirely inadequate to sever connection between the pump and the interior of the container, as the leakage 45 therethrough even with the very best construction, is sufficient to impair the vacuum to a noticeable degree.

In United States patent to Sakai 1,001,455, dated August 22, 1911, and as- 50 signed to Westinghouse Electric & Manufacturing Company, a structure is disclosed which obviates the above mentioned difficulty in a simple and effective manner by providing means whereby the valve may be 55 closed while the pump is running and liq-

uid sealing means be inserted into the passages thereof on the pump side of the valve, without opening a passage to the atmosphere. In the construction of the Sakai valve, however, it has been found quite difficult to grind the conical plug into the conical seat in such a manner as to obtain a good fit. Furthermore, in the Sakai construction it is found that, under high vacuum, the metal bearing surfaces cut each other with consequent impairment of the tightness of the valve. It is well known in mechanics that the surfaces most easily fitted to each other are planes. I have found that, by constructing one member of 60 porcelain or other vitreous material and the other member of metal, cutting and roughening are almost entirely avoided, even under high vacuum. By embodying both of 65 these features in my valve, I have provided 70 a structure which is cheap and simple in construction and highly effective in operation.

Referring to the drawing, a body member 5 is sealed into the wall 6 of a container in 75 any desired manner as, for example, by the bolts 7 and a liquid seal 8. The upper surface of the body member 5 is ground to a perfectly plane seat 9. A passage 10 extends from the interior of the container to 80 a port 11 eccentrically disposed in the seat 9. A plug member 12 of highly vitrified porcelain, or other suitable insulating gas tight material, is rotatably mounted upon the seat 9, and its lower surface is ground to 85 a true plane in order to closely engage said seat. A pivot member 13 projects into both members 5 and 12, at the central portions thereof, and centers the member 12 upon the member 5. A passage 14 extends from the 90 center of the upper surface of the member 12 to a port in the lower face eccentrically disposed with respect to the pivot 13 to such a degree that it is adapted to register with port 11 when the member 12 is suitably rotated. A compression member 15 bears on the upper surface of the member 12 and is forced downwardly thereupon by a spring 16 engaging a casing 17 which is attached to the body member 5 by bolts 18. The interior of the casing member 17 is filled with mercury, or other sealing fluid, in order to 105 entirely submerge the plug member 12 and prevent leakage over the bearing surfaces thereof. The thrust member 15 is prevented 110

from rotation by a dowel 19 projecting thereinto and engaging the casing member 17, and the plug member 12 is centered, with respect to the thrust member 15, by a sleeve 21 engaging with each member. The thrust member 15 carries a tubular extension 20 that is adapted to be connected to a pump in any desired gas-tight manner. Two holes 22 are also provided in the upper surface 10 of the plug member 12 in line with arc shaped slots 23 cut in the thrust member 15. The arc shaped slots 23 are provided with upwardly extending arc shaped barrier members 24 which serve as guides for a suitable wrench which may be inserted therethrough and into the openings 22 for the purpose of rotating the plug member 12.

The body member 9 is also provided with a passage 25 leading to a small port 26 in the seat 9 and communicating with a suitable reservoir 27 by means of a tube 28. The port 26 is so disposed with respect to the pivot 13 that, when the plug member 12 is rotated, the lower end of the passage 14 will 25 come into alignment therewith, allowing the flow of sealing fluid from the reservoir 27 into the passage 14.

Having thus described the structure of my valve, the method of manipulation is as follows: With the plug member 12 in the position shown in Fig. 1, and a pump connected to the tubular member 20, the container is exhausted to any desired degree. It will be observed (Fig. 3) that, when the plug member 12 is in this position, the openings 22 in the upper surface thereof are in alignment with the contra-clockwise ends of the arc shaped slots 23 in the thrust member 15. The desired vacuum having been obtained, a suitable wrench is inserted through the slots 23 into the openings 22 and the plug member 12 is turned to the position shown in Figs. 2 and 4 where the passage 25 is in alignment with the port 14 and the openings 22 are in alignment with the clockwise ends of the arc shaped slots 23. The pressure of the atmosphere on the upper surface of the sealing fluid in the reservoir 27 and the absence of gas pressure within the passage 14 cause the flow of sealing fluid into the latter in any desired amount. The plug member 12 is then rotated backwardly until the flat seat 9 completely covers the lower end of the passage 14, when the device may be left for any desired period without any appreciable leakage, the sealing fluid within the member 17 and within the passage 14 effectively sealing all possible leakage paths.

When it is desired to readmit air to the interior of the container 6, atmospheric pressure is first admitted to the pipe 20, and the passage 14 is then placed in alignment with the port 26, whereupon, gravity causes the flow of the sealing fluid from the passage 14 back to the reservoir 27. The plug mem-

ber 12 may then be turned so that the passage 14 is in alignment with the port 11, whereupon free communication with the interior of the container 6 is established.

I claim as my invention:

1. A valve comprising a body member, a rotatable plug member bearing thereupon in a flat surface, and means for introducing a sealing fluid into the fluid passage and for withdrawing it therefrom without opening 75 said passage to the atmosphere.

2. A valve comprising a body member provided with a flat seat having a port therein, a plug member bearing on said flat seat, adapted to be rotated thereon and having a suitable port so located as to align with the port in the body member in one position of the plug member, and a body of sealing fluid overlying the plug member.

3. A valve comprising a body member 85 provided with a flat seat having a port therein, a plug member bearing on said flat seat, and adapted to be rotated thereon, and having a suitable port so located as to align with the port in the body member in one 90 position of the plug member, and a body of sealing fluid overlying the plug member, said members being constructed of dissimilar materials.

4. A valve comprising a body member 95 provided with a flat seat having a port therein, a plug member bearing on said plane seat, adapted to be rotated thereon, and having a suitable port so located as to align with the port in the body member in 100 one position of the plug member, and a body of sealing fluid overlying the plug member, one of said members being formed from metal and the other of said members being formed from porcelain.

5. A valve comprising a metallic body member provided with a flat seat having a port therein, a plug member of vitreous material bearing on said plane seat, adapted to be rotated thereon and having a suitable 110 port so located as to align with the port in the body member in one position of the plug member and a body of sealing fluid overlying the plug member.

6. A valve comprising a body member 115 provided with a plane seat having a main port and an auxiliary port therein, a plug member bearing on said plane seat, adapted to be rotated thereon and having a suitable 120 port so located as to align with the main port in the body member in one position of the plug member and to align with the auxiliary port in the body member in another position of the plug member, a body of sealing fluid covering the interior joint between the two 125 members, and means for introducing sealing fluid through the auxiliary port to seal the interior joints between the two members, when desired.

7. A valve comprising a body member 130

provided with a plane seat having a port therein, a plug member bearing on said plane seat, adapted to be rotated thereon and having a suitable port so located as to aline 5 with the port in the body member in one position of the plug member, a body of sealing fluid overlying the plug member, and means for filling one of said ports with sealing fluid when they are not in alinement and 10 for removing said fluid before the ports are brought into alinement.

8. In a stop cock, the combination with a body member having a main passage and an auxiliary passage extending therethrough 15 and having a plane seat on one side thereof, each of the passages terminating at one end in said seat, of a plug member bearing upon said plane seat, rotatable about an axis perpendicular to the seat, and having a main 20 passage extending therethrough, the ports at the seat being eccentrically disposed with respect to said axis, means for rotating the plug member so that, in one position, the port therein registers with the port of the 25 main passage through the body member, in another position the port of the plug member registers with the port of the auxiliary passage through the body member, and in another position the port in the plug member 30 is closed by the plane seat, and means for introducing and withdrawing sealing fluid through the auxiliary passage.

9. The combination with a valve including fixed and movable members, each of 35 which is provided with a port therethrough, of a reservoir containing sealing fluid and communicating with an auxiliary port in one of said members, and means whereby said movable member may be so turned that 40 said auxiliary port will be brought into alinement with one of said main ports and said sealing fluid caused to flow into and seal said main port under the influence of the pressure of the medium within said main 45 port.

10. The combination with a valve including fixed and movable members, each of which is provided with a port therethrough, of a reservoir containing sealing fluid and 50 communicating with an auxiliary port in said fixed member, and means whereby said movable member may be so turned that said auxiliary port will be brought into alinement with the main port therein and said 55 main port will be sealed by fluid from said reservoir under the influence of the pressure of the medium within said port.

11. The combination with a valve including fixed and movable members, each of 60 which is provided with a port therethrough, of a reservoir containing a sealing fluid subject to substantially constant pressure on the surface thereof, an auxiliary port in said fixed member, and means whereby said movable member may be so turned that the main 65

port therein will aline with said auxiliary port and said fluid be drawn up to seal said main port when the pressure therein is less than that on the surface of the fluid in said reservoir. 70

12. A combined closing and sealing valve comprising fixed and movable members, each of which is provided with a main port therethrough, said main ports being in alinement in the open position of the valve, a 75 reservoir containing a sealing fluid and subject to pressure greater than that existing within said main port when it is desired to close the valve, an auxiliary port in said fixed member in connection with said fluid, so and means whereby said movable member may be turned to bring the port therein into alinement with said auxiliary port in order to force sealing fluid up thereinto and whereby said movable member may be further 85 turned so that the port therein is closed and sealed.

13. In a valve, the combination with means for providing a fluid passage, of means for mechanically closing said passage and for 90 sucking sealing liquid over said mechanical closure.

14. In a valve, the combination with means for providing a fluid passage, of means for mechanically closing said passage and for 95 sucking sealing liquid over said mechanical closure, and means for subsequently closing the path of entrance of said sealing liquid.

15. In a valve, the combination with means for providing a fluid passage, of means for 100 mechanically closing said passage and for sucking sealing liquid over said mechanical closure, and means for raising the pressure in the portion of said passage exposed to the surface of the sealing liquid to allow 105 the escape thereof.

16. In a valve, the combination with means for providing a fluid passage, of means for mechanically closing said passage, for then admitting a sealing liquid over said mechanical closure and for then closing the path of entrance of said sealing liquid, and means for raising the pressure within the portion of said passage exposed to said sealing liquid, whereby, when said closing means is 110 operated in the reverse direction, the sealing liquid is first permitted to escape and said fluid passage is then reopened. 115

17. In a valve, the combination with means for providing a fluid passage, said means 120 comprising fixed and movable members provided with alining ports therethrough, of means for turning said movable member to first destroy said alinement and close said fluid passage, then to admit sealing liquid 125 under the influence of external pressure and then to prevent the escape of said sealing liquid, and means for raising the pressure within the portion of said fluid passage exposed to said sealing liquid, whereby, when 130

- said movable member is returned to its original position, said sealing liquid is first expelled and said fluid passage is then re-opened.
- 5 18. In a liquid-sealed valve arranged for open, closed and sealing positions, the combination with a base member provided with a horizontally disposed seat, of a valve member mounted to rotate upon said seat and
10 provided with a port therethrough eccentrically disposed at its seated end and adapted to be placed in communication with one portion of a fluid line at its other end, said seat being provided with two ports, eccentrically disposed with respect to the axis of rotation of said valve member, one of said ports being adapted to be placed in communication with the other portion of said fluid line and the remaining port being in
15 communication with a reservoir of sealing liquid, means whereby said valve member may be turned so that the two fluid line ports are in registry for the open position, the valve port is in registry with the sealing
20 port for the sealing position and the valve port is closed by said seat in the closed valve position.
- 25 19. In a liquid-sealed valve arranged for open, closed and sealing positions, the combination with a base member provided with a horizontally disposed seat, of a valve member mounted to rotate upon said seat and
- provided with a port therethrough eccentrically disposed at its seated end and adapted to be placed in communication with one portion of a fluid line at its other end, said seat being provided with two ports, eccentrically disposed with respect to the axis of rotation of said valve member, one of said ports being adapted to be placed in communication with the other portion of said fluid line and the remaining port being in communication with a reservoir of sealing liquid, means whereby said valve member may be turned so that the two fluid line ports are in registry for the open position, the valve port is in registry with the sealing port for the sealing position and the valve port is closed by said seat in the closed valve position, means whereby a substantially uniform pressure may be maintained on the surface of the fluid in said reservoir and means whereby the pressure within the port of said movable member may be adjusted to values either equal to or less than that within said reservoir.
- 30 In testimony whereof, I have hereunto subscribed my name this 29th day of May, 1914.

EDWARD E. ROSE.
